COLLAR FORM

Anthony W. Serio, Elmira, N. Y.

Application September 14, 1944, Serial No. 554,065

8 Claims. (Cl. 219—19)

1

This invention relates to a collar form. The invention is more particularly directed to a collar form which acts as a dryer to set the starch in the collar of a shirt and also to effect a smoothing of the collar neck band. This collar form moreover effects setting of the collar and the band in its natural round condition, and thereby provides greater comfort to the wearer of the shirt in that the collar is of the contour of the wearer's neck and that all wrinkles and uneven surfaces of the neck band of the collar have been removed.

It is customary in ironing a shirt, upon completion of ironing the shirt, to button the shirt collar and fold the shirt. As this buttoning and folding is usually performed after the shirt is ironed, the collar has a tendency to take an out-of-round shape and the neck band therefore is wrinkled. Under these conditions the starch in the collar and neck band set and when the wearer applies the shirt and the collar about his neck there are wrinkles in the collar band which irritate the neck, and the collar being out-of-round, must be shaped by the hands of the wearer to effect a round condition and fit about the neck.

This collar form is designed particularly for domestic use by a laundress in the home, but it may well be used in commercial laundry establishments. In using the present collar form, the laundress proceeds with the ironing of the shirt in the usual way until the shirt is completely ironed and then after the shirt is ironed, the collar form is inserted within the buttoned neck band of the collar, and within a few minutes effects a setting of the starch of the collar and neck band and a smoothing of the interior of the neck band. When this is completed, the laundress has had about time to iron another shirt, and therefore the ironing of the shirt and inserting of the collar form, which acts as a dryer, can be repeated as long as there are shirts to be ironed without any delay by the collar form to effect its setting of the starch in the collar and neck band and smoothing of the neck band.

It is an object of my invention to provide a collar form which acts as a dryer for setting the collar and neck band in circular or round shape and eliminate any wrinkles or uneven surfaces of the collar neck band.

It is another object of my invention to provide a collar form consisting of two similarly-shaped sections which are automatically expandable so as to permit ready insertion within the buttoned neck band of a shirt collar.

It is another object of my invention to pro-

2

vide a collar form which is electrically heated and having a plurality of expandable sections so as to permit ready insertion within a buttoned collar and effect setting of the same and the neck band and smoothing of the collar band.

It is another object of my invention to provide a collar form which is electrically heated and provided with suitable guards so that the user will not burn or scorch her hands when inserting or removing the device from a shirt collar.

A still further object of the invention is to provide a collar form consisting of expandable similarly-formed sections and handles from each section extending upwardly therefrom which permit of ready grasp of the user so as to bring the two sections toward each other and automatically lock the same for insertion in a collar of a shirt, and providing means for release of the two sections for automatic expansion to set the collar and neck band in circular or rounded condition and simultaneously effect smoothing of the interior of the collar band.

With these and other objects in view, the invention consists in the construction and novel combination and arrangement of parts herein-after fully described, illustrated in the accompanying drawings and pointed out in the claims hereto appended, it being understood that various changes in the form, proportion, and minor details of construction within the scope of the claims, may be resorted to without departing from the spirit or sacrificing any advantages of the invention.

In the drawings:

35 Fig. 1 is a perspective view of the collar form;
Fig. 2 is a top plan view;

Fig. 3 is a transverse sectional view on the lines 3—3 of Fig. 2 looking in the direction of the arrows;

40 Fig. 4 is a transverse sectional view on the lines 4—4 of Fig. 3; and

Fig. 5 is a longitudinal sectional view on the lines 5—5 of Fig. 2.

45 The invention will be more readily understood by referring to the drawings wherein the collar form as a whole is denoted at C and consists of two similarly-shaped arcuate sections 6 and 7. These sections 6 and 7 are of substantially the same shape as the conventional collar which is attached to a shirt. In other words, the form ends 6' and 7' are pointed in the same manner as the points at the ends of a shirt collar. The sections are preferably made of metal and the exterior surface of each is smoothed and polished.

50 Each section consists of a rounded outer

arcuate band 8 and a similarly-rounded arcuate inner band 9. The forward end 10 of each outer arcuate band 8 is flanged at a right angle as is also the forward end 11 of each of the inner arcuate bands 9. The two right angle flanges 10 and 11 are in overlapping and contacting relationship, and thus there is provided a space or chamber 12 within each of the arcuate members 8 and 9. The rear ends of the arcuate members 9 are hingedly connected together by a conventional piano-type hinge 13 and a pintle 13' is inserted in the inter-connected eyes of the hinge to hold the two sections together, the hinge being interiorly of the collar form as shown. Opposite the hinge 13, there is a shield 14 which closes up the gap when the two sections are brought toward each other. This shield may be suitably spot welded within the chamber of the two sections, and is preferably spot welded adjacent the extreme outer edge of the outer section 8, but may be otherwise attached thereto.

The two arcuate sections 8 and 9 are held together by means of a plurality of screws 15 which pass through the outer section into screw threads in the inner section 9.

Disposed within the chamber 12, formed by the inner and outer sections 8 and 9, there is a conventional electrical heating element 16 on either side of which there is disposed an asbestos sheet 17. A suitable thermostat (not shown) may be embodied in order to control the heat emanating from the heating element 16.

Each section 6 and 7 has its upper edge 18 and its lower edge 19 flanged at a right angle thereto, which flanges overlap similarly-formed right angle flanges 20 and 21 on the inner arcuate sections 9. This construction permits a complete enclosure for the electrical heating element 16 within the chamber 12 of each of the arcuate sections.

Suitable handles 22 and 23, preferably of fibrous non-heat conducting material are attached at diametrically opposed points within the collar form by means of securing elements in the form of a plurality of screws 24 which pass through the innermost arcuate sections 9 and are screw-threaded in engagement with the lower projecting portions 22' and 23' of the handles 22 and 23. It will be seen that the handles 22 and 23 project upwardly above the top of the collar form as a whole. The right handle 23 has a passageway or opening 25 therein which serves as a means for the introduction of the electrical conductor 26 therethrough and the attachment of the end of the latter to a binding post 27 which, of course, is attached to the heating element 16 within the chamber 12 in each of the arcuate sections. This binding post 27 consists of the usual contact-making screws 28 and binding nuts 29. As will be seen by Fig. 3, the end of the conductor 26' is attached in electrical transmission relation to the binding post 27. The conductor 26 with its attachment plug P is of usual construction. In order to accommodate the binding post 27, the recess 23a is provided in the lower portion of the handle 23.

The enlarged lower portions 22' and 23' are each provided with oppositely-disposed recesses 30. These recesses 30 provide a means for mounting the ends of a coil spring S therein. The function of this coil spring is to effect an expansion of the two arcuate sections 6 and 7 when such expansion is desired.

The handles adjacent the top of the collar form are provided with semi-circular guard means 30. These guards are preferably integral with each

handle 22 and 23 as will be clearly seen by referring to Fig. 3, but they may be made separately and attached to each handle. The guards 30 serve a definite purpose in that when the user 5 grasps the handles 22 and 23, there is not the slightest possibility that the user's hand or fingers will contact the upper edge of either of the arcuate sections 6 and 7. It is to be understood that these guards are formed of non-heat 10 conducting material and therefore they will not become hot when the collar form is in use. The guards are slightly spaced from the upper edge of each of the arcuate sections as indicated at 31.

A pivoted catch 32 is provided so as to maintain 15 the two arcuate sections 6 and 7 in their non-expanded condition, as shown in Fig. 2, and when released, to permit the two sections to expand, such as shown in Figs. 1 and 4. This catch 32 is preferably of metal and is pivotally mounted 20 or connected to the handle 23 as at 33 by means of a screw or other suitable securing means 34. The other end of the catch 32 is provided with an elongated slot 35, which slot is enlarged as at 36 25 at one end thereof. A suitable right angle finger piece 37 extends from the top of the catch 32 and this finger piece is preferably surrounded by a plastic or fibrous non-heat conducting shield or cover 38. A screw or similar means 39, which is provided with an enlarged head, is engaged in the slot 35 of the catch. Slot 35 permits the two sections to move toward and away from each other for a predetermined distance and to lock the two arcuate sections 6 and 7 together by means of the enlarged opening 36 which, when the catch drops down, automatically engages the 30 shaft of the screw or the like 39.

In using my collar form, it will be assumed that the two arcuate sections 6 and 7 are held in retracted positions by means of the catch 32 as shown in Fig. 2, and that a laundress has, of course, inserted the attachment plug P in a suitable electrical outlet and that the collar form is heated. Then the laundress simply inserts the heated collar form in a shirt, which has already been ironed and the collar thereof buttoned, and lets it stay there for a few minutes, during which time the starch in the collar is set in a circular or rounded condition, and simultaneously therewith the collar form effects a smoothing-out of any wrinkles in the interior of the collar band and 40 a setting of the collar band in a smoothed condition. It is to be understood that when the collar form has been inserted in the buttoned collar of the shirt, the laundress simply places a finger underneath the finger piece 37, moving the 45 same upwardly and thereby releasing the two sections to be expanded gently, yet firmly enough, by means of the spring S, to effect the smoothing of the collar band and setting the starch in the latter as well as setting the starch in the collar. 50 Then, to remove the collar form, the laundress simply grasps the two handles, moving them toward each other and this will effect an automatic locking of the two sections in retracted position, as shown in Fig. 2, due to the fact that the catch 55 55 will fall by gravity and the enlarged opening therein will engage the shaft of the headed screw 39. Then, with regard to other shirts, the same operation is repeated.

Having described my invention, what I claim is:

70 1. A ring-like collar form of the general configuration of a buttoned collar that is stitched to a collar neck band of a shirt consisting of two connected arcuate sections, the sections being hingedly connected together adjacent opposed ends of the sections, with the other ends thereof

free, means for heating the sections and a handle for each section extending above the collar form to be grasped for insertion and removal of the form from a buttoned shirt collar band attached to the shirt.

2. An electrically heated ring-like collar form of the general configuration of a buttoned collar that is stitched to a collar neck band of a shirt comprising two sections hingedly connected together interiorly adjacent opposed ends of the sections with the other ends thereof free, a handle for each section extending above the top of the form to be grasped for insertion and removal of the form from a shirt collar band, means for expanding the two sections within predetermined limits when inserted in the collar band, and a releasable lockable catch for maintaining the two sections in a retracted condition during insertion and removal of the form from the buttoned shirt collar band.

3. An electrically heated ring-like collar form of the general configuration of a buttoned collar that is stitched to a collar neck band of a shirt consisting of two sections hingedly connected together adjacent opposed ends of the sections with the other ends thereof free, means for expanding the sections, handle means connected with each section and extending above the sections, which handle means when grasped permits the said other free ends of each section to be brought toward each other in a non-expanded condition, and means for releasably locking the two sections in non-expanded condition when the form is inserted in a buttoned shirt collar band.

4. A ring-like collar form of the general configuration of a buttoned collar that is stitched to a collar neck band of a shirt consisting of two hingedly connected sections, handle means connected with each section and extending above the top thereof, electrical heating means within each section and electrically connected with each other, and an electrical conductor means extending through and beyond one of the handles and connected with the electrical heating means.

5. A collar form as described in and by claim 4 wherein a spring is disposed between the two handles and a pivoted catch is mounted on one of the handles and in engagement with means on the other handle whereby the two sections may be locked in a non-expanded condition, said catch

when being released permitting the spring to expand the two sections so as to engage the neck band of a shirt collar and effect setting of the starch therein and a smoothing of the neck band of the collar.

6. A ring-like collar form of the general configuration of a buttoned collar that is stitched to a collar neck band of a shirt consisting of two electrically heated hingedly connected sections with a handle associated with each section and extending vertically above the top thereof, each section having a top and bottom edge, and guard means extending over a substantial portion of the top edge of each section so as to prevent the user from burning of the user's fingers.

7. A collar form as described in and by claim 6 wherein the guard means is integral with each handle.

8. A ring-like collar form of the general configuration of a buttoned collar that is stitched to a collar neck band of a shirt consisting of electrically heated pivotally and relatively movably connected together sections, each section having a handle associated therewith with said handles extending vertically above the top of the form, a spring within the form for expanding the collar form and having its ends secured to each handle, and means for releasably locking the collar form in a non-expanded condition during insertion of the form in the collar band of a shirt.
